Patented December 1, 1903.

UNITED STATES PATENT OFFICE.

ERNEST F. RUECKERT, OF PROVIDENCE, RHODE ISLAND, ASSIGNOR TO
B. K. SMITH AND CO., OF PROVIDENCE, RHODE ISLAND, A FIRM.

DESIGN FOR A BROOCH-PLATE OR SIMILAR ARTICLE.

SPECIFICATION forming part of Design No. 36,648, dated December 1, 1903.

Application filed January 30, 1903. Serial No. 141,213. Term of patent 8½ years.

To all whom it may concern:

Be it known that I, ERNEST F. RUECKERT, a citizen of the United States, residing at Providence, in the State of Rhode Island, have invented a new, original, and ornamental Design for a Brooch-Plate or Similar Article.

The accompanying drawing represents a brooch-plate or similar article upon which is stamped my new, original, and ornamental design.

I claim as new and desire to secure by Letters Patent—

The ornamental design for a brooch-plate or similar article, as shown.

ERNEST F. RUECKERT.
